UNITED STATES PATENT OFFICE.

DON CARLOS TRAVIS, OF KENOSHA, WISCONSIN, AND CYRIL A. SOANS, OF OAK PARK, ILLINOIS, ASSIGNORS TO SIMMONS COMPANY, OF KENOSHA, WISCONSIN, A CORPORATION OF DELAWARE.

EXTENSIBLE BEDSTEAD.

Application filed May 16, 1921. Serial No. 469,996.

This invention relates to improvements in beds or couches but more particularly to the knock-down extensible type and has for its primary object to provide a structure of this type which is simple and strong in construction, light in weight, convenient in use, and attractive in appearance.

An important object of the invention is to provide a bed or couch of this type in which the inner corners of the shiftable section are supported directly by the head and foot rather than through the medium of the main section.

Further objects are to enable the bed to be fully extended, to strengthen the head and foot, and in general to provide a new and improved article of this class.

The many other objects and advantages of the invention will be better understood by reference to the following specification when considered in connection with the accompanying drawings illustrating a selected embodiment thereof, in which:—

Fig. 1 is a side elevation of the bedstead complete.

Fig. 2 is an enlarged section on the line 2—2 of Fig. 1 with the parts in their partially extended position.

Fig. 3 is an enlarged detail perspective view of a portion of the bedstead.

Fig. 4 is a section on the line 4—4 of Fig. 2.

Fig. 5 is an enlarged plan view, partly in section, of the bedstead with the parts in the position of Fig. 2.

Fig. 6 is a detail view of the corner support for the sliding section with the parts in the fully extended position, and

Fig. 7 is the same as Fig. 6 with the parts in the closed position.

Referring to the drawings, the bed comprises a head 10, a foot 11, a main bed-bottom section 12, and a supplemental or sliding bed-bottom section 13. The main section 12 is detachably connected at its corners to the head and foot, and these parts combine to form a complete bed of the three-piece type. The section 13 is provided with supporting legs 14 at its outer corners and its inner corners are supported directly by the head and foot.

The head and the foot may be of any suitable design or material, though these are usually made of tubular metal. Each of

these parts is provided with depending posts 53 or legs 15 connected by a member 16 forming a track on which the corresponding inner corner of the section 13 is slidably supported. These tracks 16 may be screwed or otherwise securely fastened to the legs and 60 form braces which rigidly tie said legs together and greatly strengthen the bedstead.

The main bed-bottom section comprises the usual angle iron corner pieces 17 and 17' connected at their upper extremities by similar end irons 18 carrying the link spring 19. An angle iron 20 is secured to the inner face of each of the corner pieces 17 to form therewith a channel 21. The angle irons 20 at opposite ends are connected by a strut 22 70 and tie rod 23, and a similar strut 24 and tie rod 25 connect the corner pieces 17' on the opposite side of the section. Diagonal braces 26 connect the angle irons 20 with the strut 22. The corner pieces 17 are connected with 75 their corresponding end pieces 18 by diagonal braces 27. Similar braces 28 and 29 connect the corner pieces 17' with the strut 24 and the corresponding end piece 18 respectively. Boxes 30 are secured on the end 80 face of the corner pieces 17 and 17'. These boxes 30 are open at their outer face to admit supporting members 31 secured on the corresponding corner posts of the head and foot. A pin 32 extends transversely 85 within each of these boxes and has its ends seated in the side walls thereof. This pin is adapted to enter the inclined slot 33 in the member 31 to provide an interlocking and wedging engagement between the section 12 90 and the head and foot of the bedstead. This particular detachable construction is similar to that shown in the United States patent of Charles H. Busch, No. 1,397,203, granted November 15, 1921 and reference may be 95 had thereto for a more complete description thereof. Any other suitable form of detachable connection might be substituted therefor.

The sliding section 13 of the bedstead 100 nests within the main section 12 and comprises angle iron corner pieces 34 and 35 connected at their upper extremities by angle iron end pieces 36 to support the usual link spring 37. A strut 38 and tie rod 39 105 connect the corner pieces 34. A strut 40 similarly connects the angle iron corner pieces 35. A depending plate 41 is secured

upon the inner face of each of the end pieces 36 with one of its side edges abutting one flange of the corresponding corner piece 35, and also overlapping and being riveted to the other flange of said member 35. Arms 42 are pivotally mounted on the under face of the horizontal portion of the strut 40 near its opposite ends and are adapted to swing in a horizontal plane. These arms 10 project through elongated slots 43 in the corresponding plates 41 and extend beyond the ends of the sliding section. The outer end portions of these arms rest upon the tracks 16 to form a sliding support for the 15 inner corners of the section. The lower portion of the corner pieces 35 in rear of the plates 41 are preferably cut away above the slots 43 in the plates 41. The plates 41 support the arms 42 against vertical movement 20 and likewise brace the corner pieces 35. A corner brace 45 connects the end piece 36 with the strut 40. The corner pieces 34 form floor legs to support the outer corners of the sliding sections and are preferably 25 provided with the usual castors 46. A handle 47 is secured upon the strut 38 to facilitate the extension of the section.

When the section 13 is in its nested position, the lower extremities of the corner pieces 35 on this section abut against the upturned portion of the strut 24 on the main section which forms a stop to limit the inward movement of the sliding section, as indicated in Fig. 7 of the drawing. The 30 arms 42 are swung inwardly on their pivots by the corner pieces 17 on the main section. The corner pieces 34 at the outer corners of the sliding section are in substantial alignment with the corresponding corner pieces 17 of the main section. This is made possible by the placing of the strut 22 on the angle irons 20. The inwardly projecting portion of the strut 38 passes over the upper edge of the strut 22.

When the section 13 is moved toward its extended position, the arms 42 slide upon their respective tracks 16 until the upstanding portion of the strut 22 on the main section engages the downturned portion of the strut 40 on the sliding section and prevents further extension. The arms 42 engage the corner pieces 17 before the section reaches the end of its movement but further extension is permitted by the pivotal connection of these arms. As the swinging of the arms 45 is limited by the downturned portion of the strut on which they are mounted, we have found it advantageous to form these arms with a bend at 42' to permit the full extension of the section. The relative position of the various parts at the completion of the extension movement is indicated in Fig. 7 of the drawings.

The direct sliding connection between the 65 section 13 and the head and foot of the bed

can obviously be obtained in various ways but we have found the structure herein shown and described to be advantageous because of the wide range of relative movement permitted. This enables both sections 70 to be made narrower without reducing the width of the extended bed as it practically eliminates overlapping of the fabric sections in the extended position, and ensures complete nesting in the closed position. 75

The bed-bottom sections are detached from the head and foot by merely lifting these sections to disengage the pins 32 from the members 31 and then moving the head and foot away from the sections to withdraw these members from the boxes 30. The bed would generally be shipped with the bed-bottom sections nested.

In addition to the many advantages already set forth, the weight of the bed 80 may be materially reduced by supporting the sliding section directly upon the head and foot of the bed rather than through the medium of the main section. The members forming the tracks on the head and foot 85 frames of the bed strengthen these frames and remove the strain on the tubular connections.

We are aware that many changes in the 90 form and arrangement of parts may readily be made without departing from the spirit of our invention and we reserve the right to make all such as fairly fall within the scope of the following claims.

We claim as our invention:

1. In an extensible bedstead of that type in which there are a pair of mattress supporting sections normally superposed in horizontal nested relation and relatively slidably into substantially coplanar extended position to constitute a substantially unitary mattress supporting surface of double width, the combination of a pair of end frame supports, a main stationary mattress supporting section detachably connecting and supported by said end frames, a slideable section normally underlying said main section and nested therewith and outwardly slideable with reference to the main stationary section, the inner corners of said sliding section being supported directly on said end frames, and a member interposed between each of said corners and the end frame adjacent thereto, carried by and shiftable relative to one of said two last named elements. 100

2. In an extensible bedstead of that type in which there are a pair of mattress supporting sections normally superposed in horizontal nested relation and relatively slidably into substantially coplanar extended position 105 to constitute a substantially unitary mattress supporting surface of double width, the combination of a pair of end frame supports, a main stationary mattress supporting section detachably connecting and supported by said 110

end frames, a slidable section normally underlying said main section and nested therewith and outwardly slidable with reference to the main stationary section, the inner 5 corners of said sliding section being supported directly on said end frames, and a supporting member carried by said slidable section but shiftable relative thereto and interposed between each of said corners and the end frame adjacent thereto carried by and shiftable relative to one of said two last named elements, 10 35

10 the end frame adjacent thereto carried by and shiftable relative to one of said two last named elements whereby said sliding section may be completely extended or nested without interference from said supporting member.

15 3. In an extensible bedstead of that type in which there are a pair of mattress supporting sections normally superposed in horizontal nested relation and relatively slid- 20 able into substantially coplanar extended position to constitute a substantially unitary mattress supporting surface of double width, the combination of a pair of end frame sup- 25 ports, a main stationary mattress supporting section detachably connecting and supported by said end frames, a slidable section normally underlying said main section and nested therewith and outwardly slidable with reference to the main stationary section, 30 35 the inner corners of said sliding section being supported directly on said end frames, and a supporting member interposed between

each of said corners and the end frame adjacent thereto carried by and shiftable relative to one of said two last named elements, 35 40 comprising a pivoted arm carried by said slidable section, horizontal tracks being provided on said end frames upon which said pivoted members are slidably supported, whereby said sliding section may be completely extended or nested without interference from said supporting member.

4. In a bedstead, the combination of a bed-bottom provided with arms projecting beyond the opposite ends thereof and movable 45 relative thereto, and a supporting frame provided with oppositely disposed tracks on which said arms respectively rest to form a slidable support for said bed-bottom.

5. In a bedstead, the combination of op- 50 positely disposed end frames each including a pair of corner posts, horizontal brace mem- bers respectively connecting the corner posts of said frames, a frame connecting said end frames, and a bed-bottom provided at each of 55 its inner corners with a pivotally mounted arm projecting beyond the end of the bed- bottom and resting on the corresponding brace member to form a slidable support for said corners, the outer corners of said bed- 60 bottom being supported by floor legs.
